UNITED STATES PATENT OFFICE.

WILLARD T. SEARS, OF MONTCLAIR, NEW JERSEY, ASSIGNOR TO NILES-BEMENT-POND COMPANY, OF NEW YORK, N. Y., A CORPORATION OF NEW JERSEY.

INTERLOCKING MECHANISM FOR DRILLING MACHINES.

Application filed February 18, 1920. Serial No. 359,682.

To all whom it may concern:

Be it known that I, WILLARD T. SEARS, a citizen of the United States, residing at Montclair, in the county of Essex and State of New Jersey, have invented certain new and useful Improvements in Interlocking Mechanisms for Drilling Machines, of which the following is a specification.

This invention relates to drilling machines and particularly to radial drilling machines wherein a radial drill supporting arm is vertically adjustably mounted on a supporting column. Such a machine is usually provided with means for adjusting the drill supporting arm on the column and with a clamping means for securing the arm to the column in its adjusted position. It is a particular object of this invention to provide an improved interlocking mechanism for positively preventing the simultaneous operation of these two means.

Other and more specific objects will appear as the description of the invention proceeds.

Referring to the drawings:

Figure 1 is a side elevation of a radial drilling machine embodying the present invention.

Fig. 2 is an enlarged horizontal section of a portion of the machine taken on the line 2-2 of Fig. 1, looking in the direction of the arrows.

Fig. 3 is an enlarged fragmentary side elevation of the machine showing the clamping levers in operative position.

Fig. 4 is a like view but showing the clamping levers in inoperative position.

In the drawings, I have illustrated a radial drilling machine comprising the usual base 1 with a column 2 thereon and a radial drill supporting arm 3 adjustable vertically on the column. The saddle 4 with the drill spindle 5 mounted therein is adjustably supported along the arm 3 on one side of the column and a driving means, as the motor 6, with the gearing illustrated in dotted lines in Fig. 1, is supported on the opposite side of the column. I have furthermore illustrated means for vertically adjusting the arm on the column, clamping means for securing the arm in its adjusted position, and my improved interlocking mechanism as applied to such two means to prevent the simultaneous operation thereof. While the

invention is shown as applied to the machine 55 illustrated in the drawing and is particularly applicable thereto, it should, however, be understood that in its broader aspect the improved interlocking mechanism may be applied to other constructions comprising a 60 support and adjustable means thereon.

The arm 3 is adapted to be adjusted vertically on the column 2, preferably from the motor 6 through the following mechanism. A pinion 7 keyed to the motor shaft meshes 65 with a gear 8 loosely mounted on the arm shaft 9. Connected with the gear 8 is a pinion 10 which meshes with a gear 11 on a countershaft 12. One element 13^a of a toothed clutch 13 is splined to the counter-shaft 12, the other element 13^b of such clutch being provided with a socket 14 adapted to rotatably support the end of the shaft 12 therein. The element 13^b of the clutch is keyed to the short shaft 15 having a bevel 70 gear 16 thereon meshing with a bevel gear 16' secured to a rotatable nut 17 in threaded engagement with a screw 18. This screw is non-rotatably supported on the column at 75 19 and the nut 17 serves to support the entire weight of the arm and the associated parts thereof upon the screws. Preferably 80 a ball bearing 20 is interposed between the arm and the nut, that is, between the bearing 21 on the arm and the nut. A collar 21' 85 prevents downward movement of the nut with respect to the bearing. The clutch element 13^a is adapted to be shifted by means of the clutch lever 22 having a fork 22' thereon engaging the said element. It will 90 therefore be seen that with the clutch 13 engaged, the arm 3 may be moved vertically in either direction directly from the motor 6.

The means for clamping the arm in its adjusted position to the column is particularly illustrated in Fig. 2 and preferably comprises the following mechanism. Set into grooves formed at the junction of the column 2 and the arm 3 are the complementary clamping members 23 which, as will 95 hereinafter appear, move up and down with the arm 3 and also are adapted to engage against the column 2 when it is desired to hold the arm 3 in the adjusted position. Extending through these clamping members 100 23 are the rods 24, each rod at one end being provided with holding and check nuts 25 and being prevented from rotation by any

suitable means, while their other ends are furnished with adjusting nuts 26 constituting the hubs of clamping levers 27, which levers have two positions, a clamping position as shown in Figs. 1 and 3, and an ineffective or non-clamping position as shown in Fig. 4.

Cooperative with the adjusting nuts 26 and necessarily with the levers 27 and also 10 cooperative with the clutch lever 22 is a controlling member hereinafter described, which member has two positions, being adapted when in one position to permit the setting of the clamping members 23 through 15 the action of the levers 27 and when such levers are in clamping position to prevent the movement of the clutch lever 22, while when in the other position said controlling member permits the movement of the lever 22 but prevents any movement of the clamping levers while the lever 22 is in operative position. Thus when the controlling member is in the said first position the arm 3 can be clamped but cannot be raised or lowered, and when in the said second position the arm can be raised or lowered but not clamped, the said controlling member therefore acting as an interlock to prevent the simultaneous operation of both said members.

The controlling member herein illustrated comprises an elongated longitudinally sliding plate 28 having longitudinal slots 29 at its ends to receive the rods 24. This plate is 35 connected to and adapted to be moved by the clutch lever 22, such connection herein being shown as a pin or projection extending from an arm 31 on the hub of the lever 22 and engaging in a transverse elongated 40 hole 30 in the plate 28. The hub of each lever 27 is provided with a circular flange 32 and a slot 33 in each flange. A lug or pin 34 is secured to each end of the plate 28 adjacent the said hubs and in the operation 45 of the interlocking mechanism each pin is adapted to rest either on its respective flange or within the adjacent slot in the flange.

The operation of the improved interlocking mechanism is as follows. With the interlocking mechanism in the position shown 50 in Figs. 1 and 3 the clamping levers 27 are in their operative or clamping position whereby the arm 3 is clamped to the supporting column 2. The clutch 13 is in a 55 disengaged position as shown in Fig. 1 and since the pins 34 are resting on the flanges 32, the plate 28 cannot move downwardly and the lever 22 cannot therefore be rocked to engage the clutch. However, when the 60 clamping levers 27 are moved to the inoperative or clamp-releasing position shown in Fig. 4 the slots 33 are opposite the pins 34 whereupon the plate 28 is allowed to move downwardly and thereby permit the rotation of the lever 22 and the re-engagement

of the clutch 13. It will therefore be seen that the arm adjusting mechanism cannot be thrown into operative engagement when the clamping mechanism is engaged and vice versa. It will furthermore be noted that 70 when either the clutch lever 22 or the levers 27 are in the operative position the other lever or levers respectively are securely locked against any movement.

What I claim is:

1. In a drilling machine, the combination 75 of a support, an arm adjustable thereon, means for adjusting the arm, means for securing the arm to the support in adjusted position, devices for controlling the said two 80 means, and mechanism comprising a member always in operative engagement with the said devices whereby the operation of either of the said two means is positively prevented when the other means is in operative 85 position.

2. In a drilling machine, the combination 90 of a support, an arm adjustable thereon, means for adjusting the arm, means for securing the arm to the support in adjusted position, a lever for controlling each of the 95 said means respectively, and mechanism comprising a sliding plate adapted to operatively engage and prevent movement of either of said levers into operative position 95 when the other lever is in operative position.

3. In a drilling machine, the combination 100 of a support, an arm adjustable thereon, means for adjusting the arm, means for securing the arm to the support in adjusted position, a lever for controlling each of the 105 said means respectively, and a common means always in operative positive engagement with both levers for preventing the 110 operation of either of said means when the other is in operative position.

4. In a drilling machine, the combination 110 of a support, an arm adjustable thereon, means for adjusting the arm, means for securing the arm to the support in adjusted position, a lever for controlling each of the 115 said means respectively, and mechanism comprising a member having lugs thereon engaging both levers to prevent the operation of either means when the other is in operative position.

5. In a drilling machine, the combination 120 of a support, an arm adjustable thereon, means for adjusting the arm, means for securing the arm to the support in adjusted position, a lever for controlling each of the 125 said means respectively, and mechanism comprising a sliding member having lugs thereon engaging both levers to prevent the operation of either means when the other is in operative position.

6. In a drilling machine, the combination 130 of a support, an arm adjustable thereon, means for adjusting the arm, means for se-

- curing the arm to the support in adjusted position, a lever for controlling each of the said means, and a sliding member, one lever being connected to the sliding member and 5 the other lever having a pin and slot engagement with the member, whereby either lever is prevented from operating its respective means when the other lever and its means are in operative position.
- 10 7. In a drilling machine, the combination of a support, an arm adjustable thereon, means for adjusting the arm, means comprising a clamping lever for securing the arm to the support in adjusted position, a 15 lever for controlling the said adjusting means, a longitudinally sliding plate, the controlling lever being operatively connected to the plate and adapted to slide the same, and a pin and slot connection between the 20 clamping lever and the plate, the arrangement of the parts being such that the levers cannot be moved to place both the adjusting means and clamping means in operation simultaneously.
- 25 8. In a drilling machine, the combination of a support, an arm adjustable thereon, means for adjusting the arm, means comprising a clamping lever for securing the arm to the support in adjusted position, a 30 lever for controlling the said adjusting means, a longitudinally sliding plate, the controlling lever being operatively connected to the plate and adapted to slide the same, a flange provided with a slot therein 35 on the hub of the clamping lever, and a pin on the plate adapted in the operative position of the controlling lever to seat in the slot and thereby prevent movement of the clamping lever and in the operative position of the clamping lever to seat on the flange and thereby prevent movement of the controlling lever.
9. In a drilling machine, the combination of a column, an arm vertically adjustable thereon, means for so adjusting the arm, 45 means for securing the arm to the column in adjusted position, a lever on the arm for controlling each of the said means respectively, and mechanism on the arm for preventing movement of either of said levers 50 into operative position when the other lever is in operative position.
10. In a drilling machine, the combination of a column, an arm vertically adjustable thereon, means for vertically adjusting the 55 arm on the column, a hand operated clamping lever on the arm for securing the arm to the column in adjusted position, a lever for controlling the adjusting means, and mechanism on the arm for preventing movement of either of said levers 60 into operative position when the other lever is in operative position.
11. In a drilling machine, the combination of a column, an arm vertically adjustable 65 thereon, a drill spindle mounted on the arm, power means on the arm for operating the spindle, screw means for adjusting the arm vertically on the column, a clutch connection between the power means and screw 70 means, clamping means for securing the arm to the column in adjusted position, a lever for controlling the clutch, a lever for controlling the clamping means, and mechanism for preventing the placing of the two levers 75 into operative position simultaneously.

In testimony whereof, I hereto affix my signature.

WILLARD T. SEARS.
